UNITED STATES PATENT OFFICE.

FREDERICK LOBL, OF MIDDLEBORO, MASSACHUSETTS.

DESIGN FOR AN ICE-BAG RING.

54,553.

Specification for Design.

Patented Mar. 2, 1920.

Application filed April 11, 1918. Serial No. 228,061. Term of patent 7 years.

To all whom it may concern:

Be it known that I, FREDERICK LOBL, a subject of the Emperor of Austria, and a resident of Middleboro, county of Plymouth, and State of Massachusetts, have invented a new, original, and ornamental Design for an Ice-Bag Ring, of which the following description, in connection with the accompanying drawings, is a specification.

Figure 1 is a perspective view of the top of a novel ice bag ring, consisting of a tubular piece of material, the upper end of which

is expanded and then downwardly turned leaving a gracefully curved edge with a gradually inwardly tapering concave flange separated somewhat from the body of the ring.

Fig. 2 is a perspective view of the bottom of my novel ice bag ring.

I claim:

The ornamental design for an ice bag ring, as shown and described.

In testimony whereof, I have signed my name to this specification.

FREDERICK LOBL.
